CHARLES E. SPARKS, OF ALTON, ILLINOIS.

METHOD AND APPARATUS FOR SEWING BAGS AND OTHER ARTICLES.

Application filed June 30, 1924, Serial No. 723,191. Renewed June 15, 1925.

This invention relates to the manufacture of cloth bags and various other articles in which one or more relatively long seams are sewed in a piece of fabric.

5 The main object of my invention is to provide a method of sewing bags and other articles, which makes it practicable to use an automatic sewing apparatus in conjunction with high speed apparatus that performs other operations on the piece of fabric from which the article is constructed, such, for example, as printing, cutting and folding machinery of the kind now generally used in the manufacture of cloth bags.

10 Another object is to provide a method of sewing fabric bags and other articles provided with relatively long seams, that reduces the number of operatives required in the manufacture of such articles; overcomes the necessity of running the sewing machines at an excessively high speed and makes it practicable to use short stitches in the side seam and bottom seam of a cloth bag.

15 And still another object is to provide a practicable apparatus for sewing bags and other articles in accordance with my invention.

To this end I have devised a method of 20 sewing bags and other articles, which is characterized by arranging the piece of material from which the article is constructed in a certain position on a carrier that moves in a definite path, causing a sewing machine to form a seam in said piece while the carrier is in motion, and then removing or discharging the sewed piece from the carrier when the carrier reaches a certain point in its path of travel. Preferably the piece of 25 material is maintained in a fixed or stationary position on the carrier during the sewing operation and the sewing machine is moved relatively to said piece first in one direction so as to form a seam, and there- 30 after is restored automatically to its starting position so as to be in readiness to act on another piece of material when the carrier reaches the point where the pieces are applied or positioned on the carrier. When 35 my method is used in the manufacture of conventional cloth bags which are produced by sewing a seam along one side and along one end of a folded piece of fabric, I prefer to use one sewing machine to form the longitudinal side seam of the bag and use a 40 separate sewing machine to form the trans- 45 verse bottom seam of the bag, said separate sewing machines preferably operating on the bag simultaneously, or substantially so. While I prefer to move the sewing machine 50 or machines relatively to the article during the sewing operation, it is immaterial, so far as my broad idea is concerned, whether the article is moved relatively to a stationary sewing machine, or whether a movable sew- 55 ing machine is caused to travel relatively to an article that is maintained in a stationary or fixed position, so long as the article is sustained or supported during the sewing operation by a movable part, such as a car- 60 rier, to which the article is applied at one point in the path of travel of the carrier and from which the article is removed or discharged at a different point in the path of travel of the carrier, thus giving suffi- 65 cient time for the sewing operation to overcome the necessity of operating the sewing machine at an excessively high speed. Generally, the articles to be sewed will be fed manually or automatically, one at a time, 70 to a carrier that moves in a definite path and which is provided with a number of sewing units arranged so that a number of articles are being sewed at the same time, thereby enabling the method to be embodied 75 in an automatic bag sewing apparatus that forms part of a bag manufacturing apparatus that comprises conventional high speed printing, cutting and folding machinery.

The apparatus that I have devised for 80 practicing my method can be constructed in various ways, but briefly described, it is composed of a carrier that moves in a definite path, such, for example, as a rotatable table or a revolving cylinder, a plurality 85 of sewing units mounted on said carrier and each composed of one or a plurality of sewing machines, depending on the nature of the article being formed, and means for effecting relative movement of each article 90 and the sewing machine or machines that act on same while the article is being moved by the carrier from the point at which the article is applied to the carrier to the point where the article is removed or discharged 95 from the carrier. In the apparatus herein illustrated, which is designed for use in conjunction with other apparatus used in the manufacture of cloth bags, such as printing, cutting and folding machinery, 100 the carrier consists of a revolving drum or cylinder that is provided with four sewing 105 110

units, each of which units comprises a conventional sewing machine for sewing the side seam of a bag and a separate conventional sewing machine for sewing the bottom seam of the bag. As each sewing unit on the carrier reaches a certain position in the path of travel of the carrier a piece of cloth, properly folded, is arranged in a certain position on the carrier, and thereafter, the sewing machines that act on said piece will become operative automatically and will move relatively to said piece so as to form a longitudinal seam at the side of the folded piece and a transverse seam at one end of said folded piece, said sewing machines being restored automatically to starting position at the completion of the sewing operation. At a certain point in the path of travel of the carrier the completed bag is removed or discharged from the carrier, thus leaving the sewing unit that formed the seams of the discharged bag in readiness to act on another folded piece of material, when said sewing unit reaches the point where the pieces of material are applied or positioned on the carrier. Assuming that the carrier is provided with four sewing units, as herein illustrated, four bags will be completely sewed at each cycle of operations of the carrier. It is, of course, immaterial how many sewing units the carrier is equipped with, and while I prefer to arrange the sewing machines that form the bottom seams of the bags in such a way that they move relatively to the bags on which they are operating, this is not essential, for it would be practicable to form the longitudinal side seams of the bags by movable sewing machines carried by the carrier, and form the transverse bottom seams of the bags by stationarily mounted sewing machines arranged adjacent the carrier in such a way that the movement of the carrier would feed the bags past said stationary sewing machines.

Figure 1 of the drawings is a side elevational view of an apparatus constructed in accordance with my invention for practicing my improved method of sewing bags.

Figure 2 is a fragmentary end view of the left hand end of said apparatus.

Figure 3 is a diagrammatic view, illustrating the motors and electric circuit associated with the sewing machines that form the bottom seams of the bags.

Figure 4 is a detail view, illustrating the construction of the segmental conductors and sliding brushes of said circuit.

Figure 5 is an enlarged transverse sectional view of a portion of the bag carrier, showing one of the machines used in the operation of sewing the longitudinal side seams of the bags.

Figure 6 is a top plan view of the parts shown in Figure 5.

Figures 7 and 8 are sectional views, taken on the lines 7—7 and 8—8, respectively, of Figure 5, looking in the direction indicated by the arrows.

Figure 9 is a wiring diagram of the motors associated with the sewing machines that form the side seams of the bags. 70

Figure 10 is a side elevational view of the mechanism used to apply the bag blanks to the carrier. 75

Figure 11 is a top plan view of said mechanism.

Figure 12 is a side elevational view of the bag discharging mechanism that removes the sewed bags from the carrier. 80

Figure 13 is a transverse sectional view of the carrier, illustrating one means that can be used for holding the bag blanks in operative position on the carrier during the sewing operation. 85

Figure 14 is a top plan view of a bag that has been sewed by my improved apparatus; and

Figure 15 is a sectional view, taken on the line 15—15 of Figure 14. 90

Referring to the drawings which illustrate one form of apparatus that may be used for sewing conventional cloth bags in accordance with my invention, A designates a carrier which may be of any preferred construction or type, so long as it is of such design that it will support a plurality of sewing machines and move said machines in a definite or predetermined path, past a point at which bag blanks can be applied to said carrier and maintained in a certain position thereon while the sewing machines on the carrier are forming seams in the bag blanks, the term "bag blank" being herein used to designate a rectangular-shaped piece of fabric that is doubled or folded so as to form two superimposed portions which are adapted to be connected together at one edge and at one end by seams, thus, forming a conventional cloth bag that is provided with a longitudinally-disposed side seam *a* and a transverse end or bottom seam *b*, as shown in Figure 14. In the apparatus herein illustrated the carrier A consists of a revolving cylinder or drum that is arranged in a horizontal position on a suitable supporting structure and rotated or driven continuously when the apparatus is in operation by any suitable means, such, for example, as a motor-driven pinion 1 that meshes with a gear 2 secured to a shaft 3 arranged at the center of the carrier A and rigidly connected to same. The carrier A is provided with a plurality of sewing units, preferably four, each of

which sewing units consists of a sewing machine B that is used to form the longitudinal side seam of a bag and a sewing machine C that is used to form the transverse bottom seam of a bag. 100

In the apparatus herein illustrated the carrier A consists of a revolving cylinder or drum that is arranged in a horizontal position on a suitable supporting structure and rotated or driven continuously when the apparatus is in operation by any suitable means, such, for example, as a motor-driven pinion 1 that meshes with a gear 2 secured to a shaft 3 arranged at the center of the carrier A and rigidly connected to same. 110

The carrier A is provided with a plurality of sewing units, preferably four, each of which sewing units consists of a sewing machine B that is used to form the longitudinal side seam of a bag and a sewing machine C that is used to form the transverse bottom seam of a bag. 120

In the apparatus herein illustrated the carrier A consists of a revolving cylinder or drum that is arranged in a horizontal position on a suitable supporting structure and rotated or driven continuously when the apparatus is in operation by any suitable means, such, for example, as a motor-driven pinion 1 that meshes with a gear 2 secured to a shaft 3 arranged at the center of the carrier A and rigidly connected to same. The carrier A is provided with a plurality of sewing units, preferably four, each of which sewing units consists of a sewing machine B that is used to form the longitudinal side seam of a bag and a sewing machine C that is used to form the transverse bottom seam of a bag. 125

shown the sewing machines B are arranged on the inside of the carrier A in proximity to longitudinally-disposed slots 4 in the cylindrical shell of the carrier through which bag blanks are adapted to be inserted and maintained in such a position on the exterior of the shell of the carrier that the sewing machines B can operate on said blanks and form longitudinally-disposed side seams ¹⁰ *a* in the portions of the bag blanks that project inwardly through the slots 4. It is not essential, however, that the sewing machines B be arranged on the inside of the carrier A. After a bag blank has been inserted in one of the slots 4 of the carrier the sewing machine B that is arranged opposite said slot will become operative automatically and will move longitudinally of the carrier, lengthwise of the bag blank, and thus cause ¹⁵ a seam *a* to be formed in the bag blank. When said sewing machine B reaches the end of the bag blank, thus completing the seam *a*, the needle thread of the machine is severed automatically by a mechanism ²⁰ (not shown), but which forms part of the conventional bag sewing machine, and thereafter, said sewing machine B is moved automatically in the reverse direction back to its starting position. The sewing machines ²⁵ C that are used to sew the transverse bottom seams *b* of the bag blanks are arranged on the exterior of the carrier A, at one end of same, as shown in Figure 1, and are operated in such a way that they will move circumferentially of the carrier first in one direction, thereby forming transverse seams *b* in the bag blanks, and thereafter, will return automatically to starting position at the completion of the operation of sewing said ³⁰ transverse seams. Preferably, the two machines B and C that constitute each of the sewing units are combined with mechanism that causes the machine C to start operating on the bag blank after the machine B has ³⁵ started on its movement lengthwise of the blank. Accordingly, the machines B and C operate on the bag blank simultaneously during a portion of the sewing operation, and as the carrier A is revolving at this time to move the bag blank to the point where it is discharged from the carrier, ample time is provided for the sewing operation, thus ⁴⁰ overcoming the necessity of operating the sewing machines at an excessively high speed and permitting the stitches constituting the side and bottom seams to be placed close enough together to insure seams that are tight and not liable to rip. Any suitable means can be used for applying the bag blanks to the carrier, either a manually-operable means, an automatic means or a combined manual and automatic means. So ⁴⁵ also with the means that is used for removing or discharging the sewed bags from the carrier, the particular location of the bag ⁵⁰ discharging mechanism being immaterial, so long as it is arranged at such a point in the path of travel of the carrier as to provide ample time for the operation of sewing the side seam and bottom seam and still permit ⁵⁵ the sewing units to be in readiness to act on an unsewed bag blank when each sewing unit returns to the point at which the bag blanks are applied to the carrier. ⁶⁰

In the apparatus herein illustrated each of the sewing machines B is mounted on a carriage B', as shown in Figure 5, on the inside of the carrier A that travels longitudinally of said carrier parallel to the axis about which said carrier revolves, the carriage B' ⁶⁵ being provided with rollers 5 that travel on rails or tracks 6 carried by radially-disposed arms or supporting members 7 arranged on the inside of the carrier A adjacent the ends of same and also equipped with guide rollers ⁷⁰ 8 that embrace guide rails 9 which extend parallel to the track rails 6, the co-operating rollers and rails 5, 6, 8 and 9 being so constructed and arranged that the carriage B' will not move radially with respect to the ⁷⁵ carrier A, but will be capable of moving longitudinally of said carrier. Any suitable means can be used for actuating the sewing machine B, and for moving said machine longitudinally of the carrier A first in one ⁸⁰ direction to produce the side seam of the bag and then in the reverse direction back to starting position. ⁸⁵

In the apparatus herein shown an electric motor D is associated with each of the sewing machines B, said motor being mounted on the carriage B' and having a pinion 10 rigidly secured to its drive shaft 11. A sleeve 12 that is loosely mounted on the drive shaft 11 of said motor is provided with one ⁹⁰ member of a clutch E whose other member is connected to the drive shaft 11, said sleeve 12 being used to drive the needle mechanism of the sewing machine B and also being provided with a pinion 13 that forms part of the ⁹⁵ means for moving the sewing machine over the bag blank, during the operation of forming the side seam. The pinion 13 is connected by suitable gearing with a pinion 14, shown in Figures 5 and 7, that co-operates ¹⁰⁰ with a rack 15 on the carrier A which is moved automatically into and out of engagement with said pinion 14 at certain points in the cycle of operations of the carrier A. The pinion 10 on the drive shaft 11 ¹⁰⁵ of the motor D is connected by suitable gearing with a separate pinion 16, shown in Figures 5 and 8, that co-operates with a rack 17 ¹¹⁰ on the carrier A, which is moved automatically at certain points in the cycle of operations of said carrier into and out of engagement with said pinion 16. When the carrier A reaches the point in its path of travel at which the bag blanks are applied to the carrier, the clutch E is rendered operative ¹¹⁵ ¹²⁰ ¹²⁵ ¹³⁰

so as to cause the sewing machine B to become operative and to start traveling lengthwise of the bag blank, due to the movement imparted to the carriage B' by shifting the 5 rack 15 into engagement with the pinion 14. When the carriage B' reaches the end of its stroke in this direction, or, in other words, when the sewing machine B reaches the end of the bag blank, the clutch E is tripped to 10 stop the machine B and the rack 15 is disengaged from the pinion 14. Thereafter the other rack 17 is moved into engagement with the pinion 16 so as to cause the carriage B' to move automatically back to its 15 starting position, said rack 17 being automatically disengaged from the pinion 16 when the carriage B' reaches its starting position.

Various means can be used for operating 20 the clutch E and the racks 15 and 17 that effect the above-described movements of the carriage B' and the sewing machine B mounted thereon. In the apparatus herein shown the rack 15 that is used to move the machine B longitudinally of the bag blank to form the side seam a in the bag is carried by a pair of vertically-shiftable bars 18 positioned on opposite sides of the rack 15 and connected together by pins 19, said bars 18 25 being mounted in supports 20 on the carrier A in such a way that they can move bodily towards and away from the pinion 14. A shifting rod 21 that is arranged underneath the bars 18 parallel to same, as shown in 30 Figure 7, is provided with recesses 22 that are adapted to receive the pins 19 when the rack 15 is disconnected from the pinion 14. At a certain point in the cycle of operations of the carrier A, a stationary cam 23, shown 35 in Figure 7, engages a roller 23a on the end of the shifting rod 21 and moves said rod longitudinally so as to cause the pins 19 on the plates 18 to move upwardly out of the recesses 22 in said shifting rod, thereby moving 40 the rack 15 into engagement with the pinion 14, and consequently, causing the carriage B' to start traveling lengthwise of the bag blank. When the carriage B' reaches the end of its stroke in this direction, a tripping device 24 thereon engages a stop 25 on the shifting rod 21 and moves said shifting rod longitudinally in the opposite direction, thereby permitting the pins 19 on the plates 18 to move downwardly into the recesses 22 45 in said shifting rod, whereupon the rack 15 will be disengaged from the pinion 14.

A shifting lever 26 that is associated with the clutch E is so arranged that when the carriage B' reaches the end of its stroke 50 in the direction just described, said clutch lever 26 will engage a cone-shaped tripping device 27 on the carrier A and be moved by same in a direction to render the clutch E inoperative. At about the time the clutch 55 E is rendered inoperative so as to stop the

pinion 14 and cause the machine B to cease operating, and after the rack 15 has been disengaged from said pinion 14, the rack 17 shown in Figure 8 is moved into engagement with its co-operating pinion 16 by the 70 engagement of a tripping device 28 on the carriage B' with a stop 29 on said rack. The rack 17 is sustained by a pair of pivotally-mounted links 30 connected to the carrier A, and said rack is normally maintained in 75 a position out of engagement with its pinion 16 by a spring 31. Assuming that the carriage B' is traveling in the direction indicated by the arrow in Figure 8, during the operation of forming the side seam of a 80 bag, the tripping device 28 on the carriage B' strikes the stop 29 on the rack 17 as the carriage nears the end of its stroke, and thus moves the rack 17 downwardly, 85 whereupon a retaining device 32 will move automatically into engagement with a shoulder 33 in the end of said rack and hold 90 said rack in its depressed position in engagement with the pinion 16. Immediately thereafter the carriage B' will start to travel 95 in the reverse direction back to its starting position, and just before said carriage reaches its starting position, a tripping device 34 on the carriage engages a shoulder 100 or collar 35 on a shifting rod 36 and moves the retaining device 32 out of engagement 105 with the shoulder 33 on the rack 17, whereupon said rack will move automatically 110 out of engagement with the pinion 16 under the influence of the spring 31. The sewing machine B remains inactive during the remainder of the cycle of operations of the carrier A, but when said machine B approaches the point where the bag blanks are 115 applied to said carrier, a stationary cam 37 arranged at one end of the carrier A acts upon a clutch shifting bar 38 and moves said bar in a direction to cause the clutch lever 26 to render the clutch E operative, 120 whereupon the operations previously described will be repeated, namely, the sewing machine B will be rendered operative and the carriage B' will start to move in a direction to cause said sewing machine to form a side seam a in the bag blank which 125 has just been positioned on the carrier A.

When the carrier A is rotating all of the electric motors D continue in operation, the electric current being supplied to said motors by bus bars 39 on the carrier A, provided at their ends with brushes that co-operate with stationarily-mounted collector rings 40 that form part of the energizing circuit 41, as shown in Figures 6 and 9, the motors D being electrically connected with said bus bars in such a way as to provide for the movement of the carriages B' relatively to the carrier A.

Each of the sewing machines C is mounted 130 on a supporting structure at the left hand

end of the carrier A, designated by the reference character 42 in Figure 2, that is capable of a slight oscillatory movement with relation to the carrier A, but which 5 is combined with said carrier in such a way that it will revolve forwardly with the same. An electric motor C' is associated with each of the sewing machines C and each of said motors is herein illustrated as being 10 operatively connected with its co-operating sewing machine C by a driving belt 43. Obviously, any other suitable means could be used for transmitting the power of the motors C' to the machine C. Electric current is supplied to the motors C' by a number of stationarily mounted, segmental-shaped conductors 44 forming part of the 15 energizing circuit 45, as shown in Figure 3, and each co-operating with a pair of sliding brushes 46 that are electrically connected with one of the motors C' by suitable conductors. When the carrier A is in operation the motor C' that is associated with each 20 of the sewing machines C will become operative when said machine reaches a certain point in the path of movement of the carrier A, will continue in operation for a certain period and then will become inoperative automatically when its co-operating 25 sewing machine reaches a certain point in the path of travel of the carrier. During the period each of the sewing machines C is operative said machine is moved circumferentially relatively to the carrier 30 by a pinion 47 on the shaft of its co-operating motor which meshes with a segmental rack 48 secured to the carrier A. Assuming that an unsewed bag blank has been applied to the carrier A, the motor C' that drives 35 the sewing machine C which forms the bottom seam of that particular bag blank becomes operative at a certain point in the path of travel of the carrier by reason of the brushes 46 in the motor circuit moving 40 into engagement with their co-operating segmental conductor 44. As soon as said motor starts to operate the pinion 47 on the shaft thereof which is then in mesh with its co-operating rack 48 on the carrier A 45 will start to travel forwardly over said rack in the direction indicated by the arrow in Figure 2, and will thus oscillate or bodily shift the supporting structure 42 that carries the sewing machine C and the motor C' 50 that operates said sewing machine. When said supporting structure 42 reaches such a point that the bottom seam 6 of the bag has been completed, a tripping device 49 on the end wall of the carrier A (see Figure 2) 55 engages a lever 50 that controls a clutch 51 which is used to connect the pinion 47 with the drive shaft of its co-operating motor C', and thereafter, the supporting structure 42 will return to its normal position 60 against a stop 52 under the influence 65 of the spring 53 which was placed under tension during the forward movement of said supporting structure. During the return movement of the supporting structure 42 the pinion 47 is held disconnected from its drive shaft, and when said supporting structure reaches its normal position, a second tripping device 54 on the end wall of the carrier A engages the clutch shifting lever 50 and moves the clutch 51 in 70 a direction to cause the pinion 47 to become connected to its driving shaft and be in readiness to start traveling forwardly over its rack 48 at the point in the path of travel of the carrier A where the sewing machines C start to operate on the bag blanks.

As previously stated, various means can be used for applying the bag blanks to the carrier A. The means herein illustrated for this purpose comprises a manually-operated feeding device 55 arranged at a certain point in the path of travel of the carrier A and adapted to be engaged with an unsewed bag blank, as shown in Figure 10. Thereafter, 80 said feeding device 55 is moved towards the carrier A so as to insert the unsewed longitudinal edge portion of the bag blank into one of the longitudinally-disposed slots 4 in the shell of the carrier and cause a means 85 on the carrier to engage the bag blank and strip it off the feeding device 55 as the carrier A travels past said feeding device. In the apparatus herein shown the positioning of the bag blanks on the carrier is effected automatically after the bag blanks 90 have been moved manually into a certain position, but it will be obvious that an automatic feeding mechanism might be used to arrange the bag blanks in position to be 95 engaged by devices on the carrier A that cause a bag blank to be arranged in operative position on the carrier each time one of the sewing units approaches a certain point in the path of travel of the carrier, thus 100 dispensing with the services of an operator to feed the bag blanks to the carrier, and in actual practice an automatic feeding device 105 would be used in instances where my improved sewing apparatus is used in conjunction with other machinery used in the manufacture of cloth bags, such, for example, as printing, cutting and folding machinery. The feeding device 55 of the apparatus herein shown consists of a substantially horizontally-disposed, bar-like member of approximately the same length as a bag blank 110 carried by a pair of swinging links 56 and a pair of rock arms 57 and provided with pivotally-mounted gripping fingers 58. The 115 rock arms 57 are rigidly connected to a horizontally-disposed rock shaft 59 mounted in a suitable stationary supporting structure 60 and provided at one end with a hand lever 61 that is adapted to be operated manually 120

125

130

to turn said shaft in a direction to move the feeding device 55 from the position shown in full lines in Figure 10 into the position shown in broken lines in said figure to 5 insert the edge portion of the bag blank into one of the slots 4 of the carrier A. The feeding device 55 is pivotally connected to the rock arms 57 in order that it may move relatively to said rock arms, and thus assume a substantial horizontal position 10 while it is moving inwardly through the slot 4 of the carrier, and the links 56 are used to control or govern this movement of the feeding device, said links being pivotally connected at their upper ends to blocks 62 that slide vertically in guide-ways on the supporting structure 60. The gripping fingers 58 on said feeding device are connected to a rock shaft 63 that is provided 15 at its opposite ends with arms 64 and 64^a, and when the feeding device 55 is in its inoperative position, as shown in full lines in Figure 10, the arm 64 bears against a stop 66 which causes the gripping fingers 58 to be held spaced far enough away from the feeding device 55 to receive a stationary plate 67 on which an unsewed bag blank is positioned. As soon as the rock arms 57 20 start to move forwardly during the operation of moving the feeding device 55 towards the carrier A, the arm 64 on the shaft to which the gripping fingers 58 are connected moves out of engagement with the stationary stop 66, thus permitting a spring 25 65 that acts on the shaft 63 to move the gripping fingers 58 upwardly through slots in the edge of the supporting plate 67, and thus cause the unsewed bag blank to be clamped securely against the underside of 30 the feeding device 55. Accordingly, the continued forward movement of said feeding device will cause the unsewed bag blank to be stripped off the supporting plate 67 and moved forwardly through the longitudinally-disposed slot 4 in the shell of the carrier A, the gripping fingers 58 being released automatically when the feeding device reaches the position shown in broken 35 lines in Figure 10 by means of a stop 68 on the carrier A that strikes against the arm 64^a on the gripping finger shaft 63. Before the gripping fingers are actuated to release the bag blank, however, a bag blank supporting means on the carrier that is arranged at the lower side of the slot 4 in which the bag blank is inserted and which is composed of a stationary plate 69 and a movable plate 70, moves upwardly into engagement with the bag blank and causes said 40 bag blank to become fixed on said plates by means of pins or projections 71 thereon. The movable bag blank supporting plate 70 on the carrier is pivotally mounted and is acted upon by a spring 72 that normally maintains 45 said plate in a certain position, but which permits said plate to swing outwardly during the operation of ejecting the sewed bag from the carrier, as hereinafter described. After the feeding device 55 has been inserted through the slot 4 in the shell of the carrier, 50 said device becomes locked automatically by means of a spring-actuated locking dog 73 on the supporting structure 60 that engages a lug 74 in one of the rock arms 57, thus causing the bag blank to be held in such a position that it can be stripped off said feeding device when the bag holding plates 69 and 70 on the carrier move upwardly into engagement with the bag blank. As soon as said plates have engaged the bag blank, a cam 75 on the carrier A trips the locking dog 73 and immediately thereafter the feeding device 55 will be moved automatically back to its normal position shown in full lines in Figure 10 by means of a coiled torsion spring 76 that acts on the rock shaft 55 and which was placed under tension during the operation of moving the feeding device 55 towards the carrier.

The pins 71 on the bag blank supporting means on the carrier maintain the bag blank in operative position on the exterior of the carrier, but in order to eliminate the possibility of the bag blanks shifting or becoming disarranged, I prefer to provide 60 the carrier A with a pneumatic holding means which may consist of a plurality of suction devices 77 arranged on the inner side of the shell of the carrier and connected with a manifold 78, as shown in Figure 13, in which a partial vacuum is maintained by means of a suction pump 78^a.

Any suitable means can be used for removing or discharging the sewed blanks from the carrier A. In the apparatus herein shown the discharging or removing mechanism consists of a stationary cam 79 arranged in proximity to the carrier A in such a position that an actuating arm 80 on each of the movable bag blank supporting plates 70 on the carrier will travel over said cam, and thus cause said plates to swing outwardly, as shown in Figure 12, when said plates travel past the cam 79, thereby arranging the sewed blanks in a position where they can be engaged by an ejecting device 81 which strips said sewed bag blanks off the carrier. The ejecting device 81 is similar to the feeding device 55, previously described, in that it consists of a bar-like member arranged longitudinally of the carrier and connected to a pair of rock arms 82 which are secured to a spring-actuated rock shaft 83 carried by a stationary supporting structure 84. A plurality of spring-actuated gripping fingers 85 that are associated with said ejecting device are secured to a shaft 86 which is provided at one end with an arm 87 that bears against a stationary stop 88 when the ejecting device is 100 105 110 115 120 125 130

in position to receive a sewed bag blank, said arm and stop co-operating with each other to hold the gripping fingers 85 spaced away from the ejecting device 81. Normally, the ejecting device 81 is maintained in the position shown in full lines in Figure 12 by means of a pivotally-mounted, spring actuated locking dog 88 arranged so that one end of same will engage a notch 89 in one of the rock arms 82 and its opposite end will be in position to co-operate with a cam 90 on the carrier A. Assuming that the carrier is revolving anti-clockwise the arm 80 on the movable bag blank supporting plate 70 on the carrier with which a completely sewed bag blank is engaged will strike against the stationary cam 79 at a certain point in the path of travel of the carrier, whereupon said plate 70 will swing outwardly, as shown in Figure 12, and thus cause the sewed longitudinal edge of the bag blank to be moved into the zone of the ejecting device 81. The continued forward movement of the carrier A causes the cam 90 thereon to trip the locking dog 88, and as soon as said locking dog is tripped, the arms 82 that carry the ejecting device 81 will swing downwardly into the position shown in broken lines in Figure 12, the gripping fingers 85 closing automatically during the first portion of the downward movement of said arm, and thus causing the bag blank to be clamped against the ejecting device 81 and stripped off the carrier by the downward movement of the arms 82. When said arms reach the end of their downward stroke a stationary stop engages an arm 87^a on the shaft 86 to which the gripping fingers 85 are connected, and thus automatically moves said gripping fingers away from the ejecting device 81, whereupon the sewed bag blank will be released from the ejecting device and deposited on a pile of sewed bags. Thereafter the ejecting device 81 is moved upwardly back to its former position by the operator pressing downwardly on a hand lever 91 connected to the shaft 83. As soon as the arm 80 on the plate 70 on the carrier leaves the cam 79, said plate returns to its normal position shown in Figure 10, due to the pressure exerted on same by its co-operating spring 72, thereby causing said plate to be ready to strip an unsewed bag blank from the feeding device 55 when it reaches said feeding device.

Having thus described my invention, what I claim as new and desire to secure by Letters Patent is:

1. An apparatus for sewing cloth bags and similar articles, comprising a carrier that moves in a definite path and which is adapted to receive the article to be sewed, a sewing machine on said carrier, means for causing said sewing machine to start operating automatically on the article, after it

has been positioned on the carrier and moves longitudinally of said article first in one direction and then back to starting position, thus forming a longitudinal seam in the article, and a separate and distinct sewing machine arranged so that it will form a transverse seam in the article while the article is traveling to a point at which it is removed from the carrier.

2. An apparatus for sewing cloth bags and similar articles, comprising a carrier that moves in a definite path and which is adapted to receive the article to be sewed, means for maintaining said article in a certain position on the carrier, a plurality of separate and distinct sewing machines on the carrier, and means for causing said machines to travel over said article in different directions, thus forming seams in same while the article is being moved to a point from which it is discharged from the carrier.

3. An apparatus for sewing cloth bags and similar articles, comprising a carrier that moves in a definite path, means for maintaining an article in a certain position on said carrier, two automatic sewing machines that move with the carrier, means for causing said sewing machines to travel over the article in directions at right angles to each other while the carrier is in motion, thus forming seams in the article, and means for removing the sewed article from the carrier before the carrier completes its cycle of operations.

4. An apparatus for sewing cloth bags and similar articles, comprising a carrier that moves in a definite path, a plurality of separate and distinct automatic sewing units that move with said carrier, means for feeding an article onto said carrier in position to be acted upon by one of said sewing units each time one of said units passes a certain point in the path of travel of the carrier, and means for removing or discharging a sewed article from the carrier as each unit passes a different point in the path of travel of the carrier.

5. An apparatus for sewing cloth bags and similar articles, comprising a carrier that moves in a definite path, a plurality of sewing units that move with said carrier, each of which units comprises two separate and distinct automatic sewing machines, means for positioning a blank on said carrier each time a sewing unit of the carrier approaches a certain point in the path of travel of the carrier, and means for causing the sewing machines constituting each of said units to start operating automatically on the blank after it has been applied to the carrier, move over said blank in directions to form angularly-disposed seams in the blank, and then return to starting position so as to be in readiness to begin operating on another blank by the time said machine

have returned to the point at which the blanks are applied to the carrier.

6. An apparatus for sewing cloth bags and similar articles, comprising a carrier 5 that moves in a definite path, a means located at one point in the path of travel of the carrier for applying articles to the carrier, a means located at a different point in the path of travel of the carrier for removing sewed articles from the carrier, and means on the carrier for automatically sewing seams in the article while it is traveling between said two points.

7. An apparatus for sewing cloth bags, 15 comprising a revolving drum, means for holding a bag blank in a certain position on said drum, a sewing machine carried by said drum, and means for causing said sewing machine to travel over the blank on the 20 drum and form a seam in the blank while the blank is being moved to a point at which it is removed from the drum.

8. An apparatus for sewing cloth bags, 25 comprising a revolving drum, means for holding a bag blank in a certain position on said drum, two separate and distinct sewing machines that revolve with said drum, and means for causing said machines to form a side seam and a bottom seam in the blank 30 while the drum is moving the blank from the point at which it was applied to a point from which it is removed from the drum.

9. An apparatus for sewing cloth bags, 35 comprising a revolving drum on which a bag blank is adapted to be applied, a sewing machine on said drum, and means for causing said sewing machine to travel longitudinally of the drum and then return automatically to starting position so as to form a seam in 40 the blank during a certain period in the cycle of operations of the drum.

10. An apparatus for sewing cloth bags, 45 comprising a revolving drum, two automatic sewing machines that revolve with said drum, means for holding a bag blank on said drum in position to be acted upon by said sewing machines, and means whereby one of said sewing machines will be caused to travel longitudinally of the drum 50 and then return to starting position and the other sewing machine will be caused to travel circumferentially of the drum and then return to starting position during a certain period in the cycle of operations of the 55 drum so as to form a side seam and a bottom seam in the blank.

11. An apparatus for sewing cloth bags, 60 comprising a revolving drum, two sewing machines arranged so as to revolve with the drum, means for holding a bag blank in a certain position on said drum while the drum is traveling from a point at which blanks are applied to a point from which sewed blanks are removed from the drum, and 65 means for causing said sewing machines to

operate on the blank simultaneously to form a longitudinally-disposed seam and a transverse seam in the blank and then return automatically to starting position during each cycle of operations of the drum. 70

12. An apparatus for sewing cloth bags, 75 comprising a revolving drum whose shell is provided with a plurality of longitudinally-disposed slots, a plurality of sewing units arranged to move with the drum and each comprising a sewing machine arranged on the interior of the drum and a separate sewing machine arranged on the exterior of the drum, means for inserting the edge portion of a bag blank in each of said slots 80 as the drum moves past a certain point in the path of travel of the drum, and means whereby the sewing machines on the interior of the drum will be caused to travel longitudinally of the blank and the sewing machines on the exterior of the drum will be caused to travel transversely of the blanks during that portion of the cycle of operations of the drum in which the blanks are traveling towards the point at which they are discharged from the drum. 85

13. An apparatus for sewing cloth bags, 90 comprising a revolving drum, means located at one point in the path of travel of the drum for applying bag blanks to the drum, which blanks are adapted to be discharged at a different point in the path of travel of the drum, a plurality of side seam sewing machines on the drum arranged to move longitudinally of same first in one direction 95 and then back to starting position, a plurality of separate and distinct end seam sewing machines, a supporting means for said end seam machines that revolves with the drum but which is capable of oscillating 100 relatively to the drum, and means whereby each of said side seam machines and each of said end seam machines will start operating automatically after the bag blank on which said machines operate has been positioned on the drum and at the completion of the sewing operation will remain inactive until they have returned to the point where an unsewed blank is applied to 105 the drum. 110

14. An apparatus for sewing cloth bags, 115 comprising a carrier that moves in a definite path, means located at a particular point in the path of travel of the carrier for applying bag blanks to same, a plurality of sewing units associated with the carrier and each comprising two electrically-operated sewing machines, and means whereby one sewing machine of each of said units will form a longitudinally-disposed side seam in the blank and the other sewing machine of the unit will form a transversely-disposed bottom seam in the blank during a certain position of the cycle of operations 120 of the carrier. 125

15. Apparatus for sewing seams in material comprising means for moving the material, and means for simultaneously forming a seam in said material transversely of the direction of motion of the material, said seaming means being mounted on and movable with the material moving means. 20
16. Apparatus for sewing seams in material comprising movable means upon which the material is mounted adapted to move in a predetermined path, and means mounted movably on said first named means, said last named means being adapted to sew a seam in said material. 25
17. Apparatus for sewing seams in material comprising a revolving carrier, means for mounting material on the revolving car- rier, and transversely operable means mounted on the carrier for sewing a seam in said material. 20
18. The method of sewing bags comprising the moving of bag material for sewing purposes and the simultaneous sewing of right-angle seams therein, one of which seams is formed parallel to the direction of the material movement. 25
19. A seaming machine comprising a carrier surface moving about an axis, means for mounting material on the surface, a sewing head moving about said axis and relatively to the carrier surface and in the same direction thereof, said head being adapted to seam said material. 30
